WILLIAM ARTHUR LOTH, OF PARIS, FRANCE, ASSIGNOR TO SOCIÉTÉ INDUSTRIELLE DES PROCEDES W. A. LOTH, OF PARIS, FRANCE.

SYSTEM OF RADIOGONIOMETRY.

Application filed April 14, 1924, Serial No. 706,592, and in France April 23, 1923.

A process and devices permitting the exact determination of the direction of magnetic and electromagnetic fields of low, medium and high frequency. This invention is characterized, generally speaking, by the use of armatures permitting the determination of the lines of force of the waves that pass through them with respect to a straight line situated at any distance from said armatures. 5 This result is obtained by evaluating the maximum and minimum variations of the current of reception. These variations are determined in the case of variable lines of force by the displacements of brushes on a 10 commutator electrically connected to the turns or elementary windings of the armature, said armature remaining stationary. The variable position of these brushes determines the direction relatively to a straight 15 line in space of the lines of force or of the electromagnetic waves passing through the windings of the armature. The commutators for collecting the current of the armatures may be so devised as to connect the turns 20 arranged in parallel or in series, to a current receiver. The contacts on these commutators are effected by means of two brushes insulated from each other. It is obvious that the brushes could be more numerous and 25 that the use of two brushes at 180° apart is only a particular example of the various possible manners of collecting the current produced in the turns of the corresponding armature by the variable magnetic or electromagnetic field.

The present invention relates to improvements in the construction of devices for collecting the currents generated in the armatures by the variable magnetic or electro- 40 magnetic field; these improvements have more particularly for their object the variation of the number of turns on the armature without having to make gaps or breaks between the turns constituting its winding.

45 In the accompanying drawing and by way of example:

Figs. 1 and 2 illustrate in plan view two different forms of construction of devices for collecting the current of the armatures, 50 made in accordance with the improvements forming the subject-matter of the present invention.

In the form of construction shown in Fig. 1 which shows the turns 2 of an armature 55 wound on a ring or on a drum, use is made

of a fixed contact 78 and of a movable contact 4. This latter may be in the form, for instance, of a rider movable on a conducting rod 79 insulated from the turns of the armature and connected to a contact 80 by its end 60 opposed to that of the fixed contact. This rider 4 rubs on the turns 2 of the armature so that a rheostat having a variable resistance and variable self inductance is thus obtained.

Supposing that a varying magnetic field 65 of low frequency passes through the turns 2 having for instance at a given moment the direction indicated by the arrow 81. If the rider is in the position 84, it will be seen that the external circuit 82 carries a current 70 the direction of which is given by the arrow 83. A current will be produced which will pass through the following circuit: rider 4, turns 2 comprised between the said rider at 75 84, and the point 78, conductor 82, amplifier 29, conductor 82, connection 80 and conducting circle 85. The value of this current will be maximum, as if the rider 4 is moved on either side of the point 84, it will be noted that the intensity of this current diminishes. 80

If the rider is placed at point 85, arranged on a diameter at right angles to the direction of the arrow 81, two currents will be produced; a current circulating from point 85, towards point 78, and the other 85 circulating from point 85 towards point 80. As the rider at point 85 divides the winding 2 in two equal parts, these currents will have the same intensity and will be of opposed 90 directions. No current will therefore circulate in the conductors 82, that is to say the intensity of reception at the telephones 21 will be minimum.

If the rider 4 is at 86, a current circulates 95 in the circuit 82, in reverse direction to the arrow indicated at 83. It is a resultant of the currents produced, on the one hand owing to the turns between 84 and 86 and, on the other hand, owing to the turns 84 and 78.

If the field is set according to the arrow 100 88, it will be seen that for a position 89, of the rider 4, symmetrical to 78, relatively to the direction 88, no current will pass through the circuit 82.

It will therefore be seen that by moving 105 the rider 4 from the position illustrated on the drawing up to the point 84, a reception of increasing intensity will be obtained. It will be maximum when the rider 4 will be at point 84. It will subsequently decrease, if 110

the rider 4 is kept on moving for annulling it (minimum reception) when the latter reaches point 85. When the reception will be maximum, the diameter passing through 5 the position occupied, at this moment, by the rider 4 on the conducting circle 89, will give the direction of the magnetic field, that is to say the direction of the arrow 81.

It is thus possible, with a fixed junction 10 and even with a single variable junction, to know the direction of the various magnetic or electromagnetic fields.

In the same way, it is possible to mechanically alter the direction of the fixed junction 15 78 relatively to the field the direction of which is to be determined. This can be effected by rotation of the conducting ring 79. This allows one to have for each direction a number of variable receiving turns.

20 Finally it is possible to use a fixed junction and several variable junctions or several fixed junctions, or several variable junctions, without changing the principle of collection of the variable electric currents induced in 25 the turns of the armature by the variable magnetic or electromagnetic fields.

Thus, differential reception is effected by comparing the intensities of the currents received in the circuits connected to the fixed 30 junctions or to the variable junction or junctions. By displacing the latter, these receptions can be rendered equal, this giving the direction of the fields sought for.

As previously indicated, it is possible to 35 take on the armature a variable number of turns, the turns being separated from each other by breaks. As indicated hereafter it is also possible to take a variable number of turns and to group them in parallel or in 40 series, at will, no break being made in the winding.

Fig. 2 illustrates, by way of example, a 45 form of construction for that purpose. 5 and 6 designate metallic brushes insulated from each other and placed at 180° ; 5' and 6' designate a similar pair of brushes. These brushes can be arranged in the same vertical plane. They do not then include any turn between them. As the angle 5, 0, 5' 50 and the angle 6, 0, 6' increase, the brushes 5 and 5' and 6 and 6' include between them an increasing number of turns. The maxima of these angles reach 180° . When they are reached, the brushes 5 and 6' on 55 the one hand then arranged on one and the same side of the armature relatively to 0, as well as the brushes 6 and 5', on the other hand, are all in the same vertical plane. The turns included between the brushes 5 60 and 5' can be connected either in parallel or in series with those included between the brushes 6 and 6', by means of a simple switch. It is obvious that the angles 5, 0, 5' and 6, 0, 6' may be caused to vary, that is to 65 say the group of turns placed between the

brushes 6 and 6' independently from each other. It suffices for this to render the brushes 5 and 6 on the one hand and the brushes 5' and 6' on the other hand, mechanically independent from each other. 70

By turning the milled head 90, the angles 6, 0, 6' and 5', 0, 5 are caused to vary. This can be carried out whether the brushes 6 and 6' or the brushes 5 and 5' move, according to equal angles, from the fictitious middle 75 line $\alpha-\alpha$, whether the brushes 5 or 5', in the first angle, or the brushes 6 or 6', in the second angle, are alone displaced, the other side of the angle remaining fixed. It is preferable to cause the two sides of the angle 80 to move towards or from the middle line according to the same extent for one and the same rotation of the milled head 90.

Another milled head might moreover be provided in order to cause this angle to vary 85 more rapidly.

The milled head 91 permits the rotation of the whole of the four brushes according to any angle for receiving in the required direction. Another milled head may also be 90 provided for a rapid rotation. It will be noted that the turns which are not used do not present any loose ends. It is obvious that with these turns any required combinations of circuits can be effected, without 95 in any way altering the principle of the reception. The milled heads 90 acts to vary the receiving turns between the brushes and 91 acts to set these receiving turns in any direction. These can be operated either 100 directly by hand or by a clockwork which may be started at will. These milled heads 90 and 91 can also be operated at a distance, being controlled by one or more clock or electric motors or the like, also controlled 105 at a distance. The milled heads 90 and 91 or the motors, are then provided with repeating devices which give at a distance the 110 number of coils comprised between the brushes or the angles made by these brushes and the direction of the bisector of their angles, at the time of the maximum or minimum of reception. This giving by the resonance the directions of the magnetic or electromagnetic fields. 115

By adding a pair of brushes to the preceding ones, it is possible to simultaneously and independently receive from another direction.

All the applications provided for the 120 other arrangements of collectors of currents on the armatures are applicable in these cases.

These same arrangements may, moreover, serve for radiation. By adding two other 125 brushes, two radiations can be obtained in two different directions. Whether at the reception or at radiation, it will be noted that the tuning of the receiving circuit or emitting circuit is obtained by means of a 130

variable self induction coil (giving also a variable capacity) all the turns of which are receiving turns, that is to say active, instead of adding, as usually done, a non-
5 receiving variable self-induction coil which introduces in the circuit impedance and damping.

What I claim as my invention and desire to secure by Letters Patent is:

- 10 1. In an electromagnetic direction finding device, a plurality of serially connected turns, means for short circuiting some of said turns, a current indicating device, means for connecting said current indicating device to the non-short circuited turns, said short circuiting means being included in the circuit of the indicating device.
- 15 2. In a system of radiogoniometry comprising an endless winding, the connection of one of the turns of the said winding with one of the conductors of the radiogoniometry station, a conducting circle extending above the whole of the said turns, a gap in the said conducting circle corresponding to the space existing between two consecutive turns, a connection connecting one of the ends, of the conducting circle to the other conductor of the radiogoniometry station, and means for connecting to the said circuit a
25 variable number of the turns of the said endless winding.
- 20 3. In a system of radiogoniometry comprising an endless winding, the connection of one of the turns of the said winding with one of the conductors of the radiogoniometry station, a conducting circle extending above the whole of the said turns, a gap in the said conducting circle corresponding to the space existing between two consecutive turns, a connection connecting one of the ends, of the conducting circle to the other conductor of the radiogoniometry station, a movable rider arranged on the said circle and rubbing on a bare portion of the turns of the said endless winding, and means for causing the position of the gap of the conducting circle to vary relatively to the turns of the
25 endless winding.
- 25 4. In a system of radiogoniometry comprising an endless winding, the connection of one of the turns of the said winding with one of the conductors of the radiogoniometry station, a conducting circle extending above the whole of the said turns, a gap in the said conducting circle corresponding to the space existing between two consecutive turns, a connection connecting one of the ends, of the conducting circle to the other conductor of the radiogoniometry station, a movable rider arranged on the said circle and rubbing on a bare portion of the turns of the said endless winding, and means for causing the position of the gap of the conducting circle to vary relatively to the turns of the
30 endless winding.
- 30 5. In a system of radiogoniometry comprising an endless winding, the connection of one of the turns of the said winding with one of the conductors of the radiogoniometry station, a conducting circle extending above the whole of the said turns, a gap in the said conducting circle corresponding to the space existing between two consecutive turns, a connection connecting one of the ends, of the conducting circle to the other conductor of the radiogoniometry station, a movable rider arranged on the said circle and rubbing on a bare portion of the turns of the said endless winding, a contact arranged at one of the ends of the conducting circle for rubbing on the bare portion of the turns of the said endless winding, and a connection connecting the end of the circle to one of the conductors of the radiogoniometry station.

bing on a bare portion of the turns of the said endless winding.

45

4. In a system of radiogoniometry comprising an endless winding, the connection of one of the turns of the said winding with one of the conductors of the radiogoniometry station, a conducting circle extending above the whole of the said turns, a gap in the said conducting circle corresponding to the space existing between two consecutive turns, a connection connecting one of the ends, of the conducting circle to the other conductor of the radiogoniometry station, a movable rider arranged on the said circle and rubbing on a bare portion of the turns of the said endless winding, and means for causing the position of the gap of the conducting circle to vary relatively to the turns of the
50 endless winding.

55

5. In a system for radiogoniometry comprising an endless winding, the connection of one of the turns of the said winding with one of the conductors of the radiogoniometry station, a conducting circle extending above the whole of the said turns, a gap in the said conducting circle corresponding to the space existing between two consecutive turns, a connection connecting one of the ends, of the conducting circle to the other conductor of the radiogoniometry station, a movable rider arranged on the said circle and rubbing on a bare portion of the turns of the said endless winding, a contact arranged at one of the ends of the conducting circle for rubbing on the bare portion of the turns of the said endless winding, and a connection connecting the end of the circle to one of the conductors of the radiogoniometry station.

65

In testimony whereof I have signed my name to this specification.

WILLIAM ARTHUR LOTH.
